UNITED STATES PATENT OFFICE.

WILLIAM H. FAUBER AND ALBERT M. PRICE, OF CHICAGO, ILLINOIS.

DESIGN FOR A CRANK-ARM FOR VELOCIPEDES.

SPECIFICATION forming part of Design No. 32,701, dated May 22, 1900.

Application filed April 23, 1900. Serial No. 14,059. Term of patent 14 years.

To all whom it may concern:

Be it known that we, WILLIAM H. FAUBER and ALBERT M. PRICE, citizens of the United States, residing at Chicago, in the county of Cook and State of Illinois, have invented and produced a new and original Design for a Crank-Arm for Velocipedes, of which the following is a specification, reference being had to the accompanying drawings, forming part hereof.

In the drawings, Figure 1 is a side elevation of a crank-arm embodying our novel design. Fig. 2 is an edge view thereof, and Fig. 3 is an inside elevation of said crank-arm.

The leading or characteristic features of a crank-arm made in accordance with our design are as follows: The crank-arm is made smaller at its outer than at its inner end, where it joins the crank-shaft, and tapers from its inner to its outer end. The outer side of said arm is composed mainly of three plane surfaces—an intermediate surface and two exterior or lateral surfaces. Said intermediate surface is widest at the outer end of the arm and extends the full width of the arm at the said outer end thereof and tapers gradually toward the inner end of the arm. At the said inner end of the arm the margins of said intermediate surface are brought together, or nearly so. The lateral oblique flat faces are disposed symmetrically, one on each side of the intermediate surface, and arranged at an angle or obliquely to said intermediate surface. The said oblique lateral flat faces are widest at the inner end of the arm, extending

at said inner end of the arm from the side edges thereof to the central line of its outer face, and taper gradually toward the outer end of the arm, where they are brought together, or nearly so. The side margins of said outer oblique surfaces meet or coincide with the side margins of the intermediate flat surfaces, so as to form two angles at either side of said intermediate surfaces extending the full length of the crank-arms. The side faces or edges of the arm are flat for a short distance inwardly from the said lateral oblique tapered surfaces of the outer face thereof, and the inner face of the crank-arm is convexly rounded. Said rounded inner surface includes all of the inner side or face and parts of the side or edge faces of the arm, said rounded inner surface merging at each side of the arm into the flat side or edge faces thereof throughout the full length of the arm. The rounded inner surface of the arm extends to the cylindric surface of the shaft and is joined to said cylindric surface by a curved surface, as clearly shown in Fig. 2.

What we claim as new is—

The design for a crank-arm for velocipedes, substantially as herein shown and described.

Signed at Chicago, Illinois, on this 10th day of April, A. D. 1900.

WILLIAM H. FAUBER.
ALBERT M. PRICE.

In presence of—

GERTRUDE BRYCE,
DOROTHY MARMON.
